UNITED STATES PATENT OFFICE

150,924

DESIGN FOR SUN SPECTACLES

Roy L. Bright, Buffalo, N. Y., assignor to Du Bois Plastic Products, Inc., Buffalo, N. Y., a corporation of New York

Application April 18, 1947, Serial No. 138,472

Term of patent 14 years

(Cl. D57—1)

To all whom it may concern:

Be it known that I, Roy L. Bright, a citizen of the United States, residing at Buffalo, in the county of Erie and State of New York, have invented a new, original, and ornamental Design for Sun Spectacles, of which the following is a specification, reference being had to the accompanying drawing, forming a part thereof.

Figure 1 is a front perspective view of sun spectacles, showing my new design. Figure 2 is a front elevational view thereof. Figure 3 is a bottom plan view. Figure 4 is a side elevational view of the same.

The essential features of my design reside in the parts shown in full lines.

I claim:

The ornamental design for sun spectacles, substantially as shown and described.

ROY L. BRIGHT.
